AKE L. ALIN, OF SPOKANE, WASHINGTON

CONCRETE FORM

Application filed July 25, 1927. Serial No. 208,091.

My invention relates to forms for use in casting concrete and refers particularly to forms which are adjustable in size to provide finished concrete shapes of different dimensions.

It is the practice in erecting concrete structures to provide forms to determine the finished shape of the structure. These forms usually are constructed of wood erected especially for the purpose and are removed when the concrete has set. It is necessary to erect a form for each structure and to provide forms of different size for different sized structures. The labor of assembling, erecting and removing the forms must be gone through with each time they are used.

It is an object of my invention to lessen materially the labor necessary to erect and remove a concrete form.

Another object of my invention is to provide a form which can be used a plurality of times without total dismantling each time.

A further object of my invention is to provide a concrete form which can be utilized on concrete shapes of different sizes.

A further object of my invention is to provide a concrete form which can be put in position and dismantled quickly and easily.

An additional object of my invention is to provide a simple locking device for an adjustable concrete form.

My invention possesses other advantageous features, some of which with the foregoing will be set forth at length in the following description where I shall outline in full that form of the concrete form of my invention, which I have selected for illustration in the drawings accompanying and forming part of the present specification. In said drawings I have shown one form of concrete form embodying my invention, but it is to be understood that I do not limit myself to such form since the invention, as set forth in the claims, may be embodied in a plurality of forms.

In the drawings:

Fig. 1 is a side elevation of a form of my invention adapted for use with a column.

Fig. 2 is an enlarged detail of a corner of the form of my invention.

Fig. 3 is a cross section of the form of my

invention adjacent a corner, the plane of section being indicated by line 3-3 in Fig. 2.

In its preferred embodiment, the concrete form of my invention preferably comprises a plurality of walls, each wall being made up of a pair of rails movable toward and away from each other in fixed relationship and each being provided with a plate, the plates overlapping to form a continuous confining surface for the concrete.

The adjustable form of my invention is capable of a variety of uses and is described herein as adapted for forming columns of concrete. It of course can be used in making beams and other structural units but finds perhaps its widest range of applicability to columns. In making the form of my invention, I preferably provide a pair of rails 6 and 7 which conveniently can be metal shapes such as angles. The rails generally are disposed in parallel relationship although in some instances they can be inclined. As disclosed in the drawing, the rails are preferably parallel and are joined by means for permitting them to be moved toward and away from each other but at the same time maintaining their parallelism.

These means preferably comprise a plurality of bars 8, which also can be metallic angles, joining the rails. The bars are apertured at each end and are pivoted to the rails at suitably spaced points. Preferably, the bars are spaced farther apart adjacent the top of the form as the load in that region is not as great as it is adjacent the bottom where the bars are more closely spaced. The plurality of pivoted bars 8 permit the rails 6 and 7 to be moved toward and away from each other with some longitudinal or axial displacement but at the same time maintain the rails in parallel relationship. A convenient form of pivotal connection between the rails and the bars 8 is by means of flat headed bolts 9 and nuts 10 which permit the dismantling of the various portions if desired.

To form an abutment for retaining the concrete within the form, each of the rails 6 and 7 is provided with a plate 12, usually of sheet metal and conveniently joined to the rail by the several bolts 9. Preferably the plates are

of thin section and overlap adjacent the mid-portion of the bars 8. The overlapping plates permit lateral expansion and contraction of the rails relative to each other but nevertheless provide a substantially continuous wall for the retention of concrete.

Means are provided for retaining the two rails 6 and 7 in fixed lateral adjustment and these means conveniently take the form of 10 apertures 13 passing thru the plates 12 for the reception of suitable fastening means such as stove bolts and nuts for securing the plates 12 together. This provides an adjustable fastening means for maintaining the width 15 of the wall formed by the plates and rails at a fixed amount. A plurality of such apertures 13 permit various lateral widths to be given the wall.

The usual column is rectangular in trans- 20 verse section and I therefore usually provide four of the described expandable walls to encompass the space for the column. The four walls are joined together by suitable fastening means which can quickly and easily be placed in position. At each corner, the angles 25 6 and 7 are preferably disposed as shown in Fig. 3. On each angle 6 and abutting the corresponding plate 12 is a strip 14 which extends for the entire length of the angle and 30 is adapted to lie against the plate 12 of the adjacent angle 7. Against the strip 14 is a strip 16 on angle 7 which extends for the full length of that angle also but is interrupted at intervals to accommodate the heads 35 of the bolts 9.

To hold the strips 14 and 16 in close abutment to prevent the escape of any concrete thru the joint at the corner, I provide a plurality of wedges 17 preferably affixed to the 40 angles 6 at intervals throughout their length and which can be suitably attached thereto as by welding. Adapted to cooperate with the wedges 17 are a corresponding number of tie strips 18 spanning the adjacent angles 45 and overlying the wedges. Each tie strip at one end is hooked to fit over the cooperating wedge 17 and at the other end is also hooked to slip over the projecting portion of angle 7. When the tie strips 18 are forced downwardly 50 over their corresponding wedges 17, they force the two angles 6 and 7 into abutting relationship and, together with strips 14 and 16, provide a very tight junction. The tie strips can readily be forced into place with a 55 hammer and can as readily be released.

The longitudinal movement of the rails 6 and 7 to vary the lateral width causes differences in the total length of the walls and for that reason I have provided means at the top 60 and bottom of my form to continue the plates 12. At the top of the column I provide a plurality of overlapping sheets 19 and 21 which are suitably bolted together. These sheets preferably lie within the overlapped plates 65 12 and are secured in place by perforated an-

gles 22 joined at appropriate points by nuts and bolts 23. The ends of plates 19 and 21 need not all terminate in a common plane, as shown in Fig. 1, but they may be of various heights and contours to accommodate a beam 70 or other shape extending across the top of the column.

At the bottom of each of the walls formed with my device, I usually leave an aperture to 75 permit cleaning out of the interior of the form, or the aperture can be sealed by a clean out plate 24 of suitable configuration which will seat between the plates 12 and the lower cross bar 8. The clean out plate 24 preferably is held in place by a tongue 26 projecting 80 from the adjacent angle 6 and passing through a perforation in the plate. A key 27 passing through a similar perforation in the tongue holds the plate 24 in place.

In using the concrete form of my invention, 85 the location of the form is preferably determined by setting a collar or frame of wood on the floor in the precise location for the column. The two rails 6 and 7 of each wall, usually four in number, are then spaced apart the 90 requisite distance and the plates 12 are fastened together by suitable bolts passing through apertures 13. The extension sheets 19 and 21 are then bolted to the plates 12 at each side and the four walls are then erected 95 to vertical position with their lower ends positioned within the collar. When the four walls are erected, the tie strips 18 are applied to the angles 7 and the various wedges 17, and are driven into place. The form is thus 100 erected and locked in position. After the four walls are erected, the extension sheets 19 and 21 are joined together and the securing strips 22 are fastened in place. When the interior of the form has been cleaned, the clean out plates 24 can be moved into position and the form is ready to receive the concrete. 105

I claim:

1. A concrete form comprising a pair of overlapping sheets, a rail on each of said sheets, a plurality of bars pivotally attached to both of said rails, and means for retaining said rails in adjusted position. 110

2. A concrete form comprising a pair of overlapping sheets having perforations therein, a rail secured to each of said sheets, means for permitting one of said rails to approach the other of said rails and for maintaining said approaching rail parallel to itself, and means passing through said perforations for maintaining said rails in selected spaced position. 115

3. A concrete form comprising a pair of intersecting walls, a flange on each of said walls, said flanges being in abutting relationship, a plurality of wedges on one of said flanges, and a plurality of tie strips engaging the other of said flanges and said wedges for securing said walls in position. 125

4. A concrete form comprising a plurality 130

of abutting walls arranged to form a polyhedron, each of said walls including a pair of overlapping sheets, means for constraining the sheets to relative lateral displacement upon relative longitudinal translation thereof, and means for securing said walls together to prevent said relative longitudinal translation of said sheets.

In testimony whereof, I have hereunto set
10 my hand.

AKE L. ALIN.
